MAIL BOX

Irving A. Levine, Woodmere, N. Y.

Application October 27, 1953, Serial No. 27,347

Term of patent 14 years

(Cl. D74—9)

To all whom it may concern:

Be it known that I, Irving A. Levine, a citizen of the United States, residing at Woodmere, Long Island, New York, have invented a new, original, and ornamental Design for a Mail Box, of which the following is a specification, reference being had to the accompanying drawing, forming part thereof, in which

Fig. 1 is a front perspective view of a mail box, showing my new design, and

Fig. 2 is a side elevational view thereof.

I claim:

The ornamental design for a mail box, substantially as shown.
